FOLDING TOY

Herman A. Feigelman, Paterson, N. J.

Application February 28, 1946, Serial No. 650,944

2 Claims. (Cl. 46—21)

1

This invention relates generally to toys and more particularly to a folding structure such as a toy fort.

It is an object of the present invention to provide a device made of two blanks which when folded along score lines and interlocked will present a fort.

It is another object of the present invention to so arrange or dispose the folding sections of blanks, so that the blanks may be interlocked in a very efficient, practical and simple manner.

These and other objects and certain advantageous features are accomplished by the novel and practical construction, combination and arrangement of parts hereinafter disclosed and illustrated in the accompanying drawing, constituting an essential part of the disclosure, and in which:

Fig. 1 is a plan view of a blank embodied in the invention.

Fig. 2 is a back plan view of another blank embodied in the invention.

Fig. 3 is a front view of a toy fort set up by folding and interlocking the blanks of Figs. 1 and 2.

Fig. 4 is a top view of Fig. 3.

Fig. 5 is a sectional elevation of the assembled fort, taken on line 5—5 of Fig. 3.

Referring now more particularly to the drawing, there is shown in Fig. 1 a blank generally indicated by the numeral 10, and in Fig. 2 a blank generally indicated by the numeral 11. These blanks 10 and 11 are made of a suitable flexible material such as paste board, card board, fiber etc.

Blank 10 is scored and die-cut to provide when set up, rear vertical wall section 12, bottom wall section or base 13, horizontal platform 14, vertical front wall section 15, spaced apart vertical end wall sections 16, 17 joined together by the vertical front wall 18. Vertical wall 12 has connected thereto a section 12a by means of the score lines 12b, the blank being die-cut so as to provide the tabs 12c extending from wall section 12 and the tabs 12d extending from 12a. The portion 12a is separated at its ends from wall section 12 by the cuts 12e.

Wall section 12 is connected to bottom 13 by score or fold line 20 and section 15 is connected to bottom section 13 by the score line 21, and section 14 is connected to 15 by the score line 22. Section 15 has extensions or tabs 15a which are slightly spaced from section 14. Hinged to section 14 by the fold line 24 is a longitudinal tab 14a, the latter being separated from section 14

2

around its mid-portion whereby a tab 14b is provided.

Wall section 12 is connected at both ends to wall sections 16 by the fold lines 25; end wall sections 16 are respectively connected to front walls 18 by the score lines 26; and sections 18 are respectively connected to the wall sections 17 by the score lines 27. Connected to each section 17 by score line 28 is a flap 29 having a tongue or tab 29c. Intermediate score line 28, the blank is die-cut so as to provide a tab 29a extending from flap 29, flap 29 being separated from section 18 by the cut 29b. In each section 18, a cut or slit 18a is provided. Connected to each section 17, by the score line 17b, is a tab 17a. From each section 16 there is struck a tab 16a which is foldable along the crease line 16b.

Connected to each section 16, by the fold line 16g, is a flap 16c having a portion 16d foldable along the crease line 16e. At the crease line 16e there is provided a slit 16f. Flap 16c and tab 16d are separated from section 13 by the cut 16h. The blank 10 is provided with the ornamental edge 19 simulating the top portion of a fort.

Blank 11 shown in Fig. 2 is scored and die-cut to provide a front wall section 30 to which are connected by means of score lines 30a, the end wall sections 31, front wall section 30 being provided with a slot 30b and a plurality of spaced tabs 30c hinged at 30d.

Elements 30e, simulating doors, are formed out of section 30 and are swingable along the fold lines 30f. Connected to section 30 by the fold line 32 is a bottom tab 33.

In setting up the fort, blank 10 is folded and portions thereof interlocked as follows:

The blank is folded at both ends along the crease lines 26, 27, 28, 16g and 16e; the tab 17a inserted in slot 16f, and tabs 29c inserted in slot 29b formed by the outward displacement of tab 16a (see Fig. 3). The blank is now folded along crease lines 20, 21, 22 and 24 so that the platform 14 assumes a horizontal position. Then the blank is folded along the crease lines 25 and tabs 15a are made to engage slits 18a. The blank 11 in Fig. 2 is now folded rearwardly along the crease lines 30a and 32 and inserted in the folded blank 10 at the rear of platform 14, the tab 14b of blank 10 being inserted in slot 30b of blank 11 and the folded end walls 31 of blank 11 abutting against the inner-face of wall 12 of blank 10. Fig. 3 shows the section 15 divided into a pair of lower front wall sections 15b, extending underneath respective cuts 18a, and an intermediate section 15c. A pair of slots 34, formed in the end walls 31 of

blank 11 as shown in Fig. 2, are designed to accommodate the tabs 29a of flap 29 as seen clearly in Fig. 5. Portion 12a extending from wall 12 is now folded downwardly into a horizontal position and the tabs 12d made to engage the slots formed by the outward displacement of tabs 30c, see Fig. 5. It will also be noted from that figure that the tabs 12c previously referred to remain upright when the portion 12a is folded down, these tabs representing battlements similar to 10 those formed by the tabs 19. The toy fort has now been set up for use.

It is thus seen that the present invention comprises simple and practical parts which can be folded and set up to comprise a toy device. The 15 device comprises a relatively few parts which may be inexpensively manufactured and assembled and which is well adapted to accomplish among others, all of the objects and advantages herein set forth.

Having thus described the invention, what is claimed as new and desired to be secured by Letters Patent is:

1. A folding toy fort made of two blanks; one of said blanks having score lines and when folded along said lines providing a vertical rear wall, a bottom wall extending forwardly from the lower edge of said rear wall, end walls extending forwardly from each of the opposite side edges of said rear wall, front wall sections extending inwardly from the front edges of said end walls and having slits formed above the lower edges thereof, side walls extending rearwardly from the inner edges of said front wall sections, said end walls, front wall sections and said side walls forming turrets extending forwardly from the opposite ends of said rear wall, an upstanding low intermediate front wall extending from the forward edge of said bottom wall, projections extending upwardly from said front wall adjacent the opposite ends thereof and engaging in said slits formed in said front wall sections, a platform extending rearwardly from the upper edge of said low intermediate front wall between said 25 projections; the other of said blanks having score lines and when being folded along said lines providing a front wall engaging between said rearwardly extending side walls and resting upon said platform in rearwardly spaced relation to said low intermediate front wall and end flaps.

extending from the side edges of said front wall; tab means connecting said front wall of said other blank to said rear wall of said first blank, and tab means connecting said side walls to said end flaps.

2. A folding toy fort made of two blanks; one of said blanks having score lines and when folded along said lines providing a vertical rear wall, a bottom wall extending forwardly from the lower edge of said rear wall, end walls extending forwardly from each of the opposite side edges of said rear wall, front wall sections extending inwardly from the front edges of said end walls and having slits formed above the lower edges thereof, side walls extending rearwardly from the inner edges of said front wall sections, said end walls, front wall sections and said side walls forming turrets extending forwardly from the opposite ends of said rear wall, an upstanding low intermediate front wall extending from the forward edge of said bottom wall, projections extending upwardly from said front wall adjacent the opposite ends thereof and engaging in said slits formed in said front wall sections, and a platform extending rearwardly from the upper edge of said low intermediate front wall between said projections; the other of said blanks having score lines and when folded along said lines providing a front wall adapted to engage between said rearwardly extending side walls and to rest upon said platform in rearwardly spaced relation to said low intermediate front wall and end flaps extending from the side edges of said front wall.
